SASH CONSTRUCTION

William S. Hamm, Elkhart, Ind., assignor to The
Adlake Company, Chicago, Ill., a corporation
of Illinois

Application October 30, 1936, Serial No. 108,414

2 Claims. (Cl. 189—76)

This invention has to do with metal window sash of the type in which a soft rubber glazing strip is positioned about the edge of the glass.

The object of the invention is to provide improved means for preventing the abutting ends of such a glazing strip from separating and leaving a gap.

A preferred embodiment of the invention is presented herein, but it will of course be appreciated that the invention is susceptible of incorporation in other slightly modified forms coming equally within the scope of the appended claims.

In the accompanying drawing:

Fig. 1 is a fragmentary side view of one of the corners of a sheet metal sash glazed in accordance with the invention;

Fig. 2 is a corresponding view, with the parts shown in separated relation; and

Fig. 3 is a transverse section through one of the rails of the sash, taken on the line 3—3 of Fig. 1.

In this sash a pane of glass 10 is supported by rubber glazing strips 11 and 12 in grooves 13 and 14 provided in hollow metal rail members 15 and 16. When the parts are assembled the ends of the glazing strips 11 and 12 are intended to abut as shown at 17 in Fig. 1, in order to provide a snug weather-tight joint between the ends.

Considerable difficulty has been experienced in the past with sash of this type due to the ends 30 of the glazing strips becoming separated from each other and leaving a gap after the parts have been assembled and the sash has been in service for a time. This difficulty has been overcome in a simple but effective manner by the hereinafter 35 described means.

Before the glazing strips 11 and 12 are fitted onto the edges of the glass short strips 18 and 19 of thin flexible adhesive tape are stuck over the edges of the glass, preferably in such manner as 40 to lap narrow margins on both faces of the glass. These strips, which will adhere firmly to the glass as soon as placed thereagainst, are positioned at opposite sides of the proposed location for the joint 17. A single strip of the adhesive tape can 45 be bent around the corner of the glass if desired, in place of two separate strips, in order to span both ends of the glazing strips 11 and 12, but as the results have been found to be substantially the same either way and as undesirable wrinkling 50 will take place at the corner with a single strip unless the excess material is notched out the use of two separate strips is recommended. Of course, if the joint between the ends of the glazing strips 11 and 12 is located between two of the corners

of the sash, instead of at one of the corners, then there is no reason why a single adhesive strip bridging both ends should not be used.

After the adhesive strips 18 and 19 have been applied to the edges of the glass the glazing strips 5 11 and 12 are applied to the edges of the glass, with their ends over the adhesive strips, and the glass, with the adhesive strips and glazing strips both on it, is then forced into the grooves 13 and 14 in the rail members. In working the glazing 10 strips into the grooves, which usually involves a sliding movement longitudinally of at least one of the rail members, the glazing strips are almost sure to become somewhat stretched, but the adhesive strips 18 and 19 will act to firmly grip both 15 the glass and the glazing strips in such a way as to prevent any separating movement of the ends of the glazing strips ever taking place, with the result that a very satisfactory joint is obtained in an exceedingly simple manner without involving any appreciable expense on account of either 20 labor or materials.

It will of course be understood that the glazing strips 11 and 12 may either be separate strips or else constitute end portions of a single long strip 25 extending about all four edges of the glass.

It will also be understood that the rail members may be of any desired construction, with some or all of the corner joints therebetween made separable to facilitate insertion and removal of the 30 glass.

I claim:

1. In sash construction, a frame, a pane of glass, glazing strips in the frame about the edges of the glass, and adhesive tape on the edges of 35 the glass between the latter and the glazing strips in adhering association with the glass and frictional engagement with the glazing strips at opposite sides of the joints present between the glazing strips.

2. In sash construction, a metal frame provided with a groove, a pane of glass positioned with its edges in the groove, a rubber glazing strip of U-shaped cross section set into the groove with its sides pressed laterally by the sides of the 45 groove into resiliently compressed engagement with the sides of the glass, and adhesive material positioned between the sides of the glass and the sides of the glazing strip in gripping relation to both the glass and the glazing strip at opposite 50 sides of the joint present between the ends of the glazing strip.

WILLIAM S. HAMM.
